UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 10, 1923. Serial No. 650,615.

This invention relates to manifolding typewriting machines of the continuous billing type, in which a continuous composite sheet or web is fed around a cylindrical platen, the web comprising several plies of work-sheets having successive corresponding forms printed thereon, said plies being sometimes separated from each other and sometimes joined at their side edges to form a fan-folded web, the various plies having carbon-sheets interleaved therebetween. The invention relates more particularly to means to facilitate the relative displacing or shifting between the carbon-sheets and the work-sheets, or, in other words, the shifting of the carbon-sheets from the typed set of forms to a fresh set of forms. The invention further relates to means for determining the relative shifting between the carbon-sheets and the work-sheets.

In the Underwood continuous billing machine, shown in the patent to Wernery & Smith, No. 1,132,055, dated March 16, 1915, a cylindrical platen is employed, and said platen is displaceable upwardly by means of a swing frame, to permit the composite web to be straightened out preparatory to displacing or shifting the carbon-sheets along the work-sheets to a fresh set of forms. There is also employed in said machine a table extending rearwardly from the platen, upon which a carbon-carrier is mounted to travel back and forth towards and away from the platen, said carbon-carrier having the ends of the interleaved carbon-sheets connected thereto, and said carbon-carrier being movable rearwardly by a handle while the work-sheets are drawn forward to a suitable gage.

A feature of the present invention is the provision of means for facilitating a relative shifting of the carbon-sheets and the work-sheets without lifting the platen, the platen being of the non-displaceable kind and consequently always in typing position. To this end there is provided a table extending from the rear of the platen, said table having a carbon-carrier movable thereon towards and away from the platen. The carbon-carrier in the present invention, however, is used to move the composite web rearwardly, so as to free it from the platen and bring the carbon-sheets to a straightened-

out position preparatory to causing relative displacing between the carbon-sheets and the work-sheets.

After the carbon-sheets have been straightened out, the leading edges of the work-sheets are then grasped by the typist and drawn forwardly above the platen, while the carbon-carrier is retained in its rearmost position, to a suitable gage which determines the amount of relative shifting movement. The typed forms may then be severed from the work-sheets, after which the composite web may be reinserted around the platen and advanced to bring the first line to be typed to the printing point.

Another feature of the invention is the provision of means for facilitating a rapid reinsertion of the composite web around the platen and also for quickly advancing the composite web the proper distance around the platen, so that the first line to be typed on the fresh forms is brought to the printing point. To this end there is provided, on the carbon-carrier table, normally ineffective feeding mechanism, said mechanism comprising a handle which may be actuated to advance the composite web, the leading end of which is conducted downwardly towards the platen by means of a deflector.

In the present invention the carbon-carrier table is pivotally mounted on a secondary table or frame secured to the typewriter carriage, so that the forward end of said carbon-carrier table may be swung upwardly to free the leading edges of the web from the web-deflector, that the leading ends of the work-sheets may be grasped by the typist and then drawn forward to a gage. Said table is also swingable to this position to facilitate the tearing off of the typed forms, there being provided for this purpose a knife which is located beneath the composite web. The knife normally occupies a position out of the path of the web, so as not to interfere with the web as it passes from the carbon-carrier table downwardly towards the platen. The knife is swung to its effective or tearing-off position, however, during the upward swinging movement of the carbon-carrier table.

Another feature of the invention relates to the provision of a handle by which the carbon-carrier table may be swung upward-

ly, said handle being so connected with the knife and the gage as to move them to their effective positions.

A further feature of the invention resides 6 in the provision of means for locking the carbon-carrier in its rearmost position when the carbon-carrier table is swung upwardly and for clamping the work-sheets, so as to prevent an accidental forward movement of 10 the carbon-sheets and the work-sheets during a sheet-gaging and carbon-displacing operation.

A further feature of the invention relates 15 to means for retaining the carbon-carrier to hold the carbon-sheets and consequently prevent accidental displacement thereof during the shifting of the work-sheets relatively thereto.

Still another feature of the invention relates 20 to means for clamping the work-sheets to prevent accidental advancement or shifting thereof during a severing operation.

Other features and advantages will hereinafter appear.

25 In the accompanying drawings:—

Figure 1 is a sectional side elevation of an Underwood typewriting machine, showing the invention applied thereto, the parts being shown in position with the bottom of 30 the typed set of forms near and below the printing point.

Figure 2 is a top plan view of the parts shown in Figure 1.

Figure 3 is a sectional side view similar 35 to Figure 1, but shows the feed-rollers cast off, the composite web drawn rearwardly around the platen, and the table-lifting handle swung upwardly to bring the knife and the gage to their effective positions.

40 Figure 4 is a view similar to Figure 3, and shows the carbon-carrier table swung upwardly to a convenient position for sheet-gaging and tearing-off of the typed forms.

Figure 5 is a fragmentary view of the forward portion of the carbon-carrier table, the parts being shown in the same position as Figure 3, except that the work-sheets have been advanced to the gage prior to severing them, as shown in dot-and-dash lines.

50 Figure 6 is a fragmentary view of the rear portion of the work-web table, showing the pivoted section thereof swung farther than in Figure 4, to clamp the work-sheets before a severing operation.

55 Figure 7 is a fragmentary sectional side view, showing the parts in position after the carbon-carrier table has been lowered, the web-feeding handle being also shown as moved bodily to bring the feed-rollers against each other.

60 Figure 8 is a view similar to Figure 7, but shows the web-feeding handle swung about its pivot to rotate the feed-roller controlled thereby, and the web advanced to the printing point.

The invention is shown as applied to an Underwood standard typewriting machine, in which type-bars 10, when operated by keys, not shown, swing upwardly and rearwardly to print against the front of a cylindrical platen 11, mounted on a carriage 12 comprising end bars 13 connected to each other by a rear bar 14 and a front bar, not shown, said carriage being mounted for letter-feed movements on a rear rail 15 and 75 a front rail, not shown, said rails being supported on the main frame 16 of the machine. The platen is secured to a shaft 17 journaled in end plates 18 of a platen-frame 20, said end plates being secured to each other by a bar 21 and a rear paper-table 22, over which a composite work-web 23 is led from the back of the machine to the rear and beneath the platen where there are provided feed-rollers 24 and 25 to assist in feeding the 80 work-web around the platen. The platen may be rotated by a finger-wheel 26 or line-space wheel 27, the latter being operable by suitable line-space mechanism, not shown. The platen-frame is supported on the carriage-frame for case-shifting movements in the usual way to present the platen to lower-case types 30 or upper-case types 31 on the type-bars. The feed-rollers may be released by mechanism operable by the regular feed-roller release handle 28, so as to provide an unobstructed path around the platen when adjusting the work-web around the platen.

90 The attachment comprises a horizontal table 32 extending rearwardly from the machine and over which the composite web 23, comprising work-sheets 33 with interleaved carbon-sheets 34, is conducted to the platen. Said table comprises two sections, namely, a relatively fixed or lower section 35 and a swingable or upper section 36. The relatively fixed section 35 comprises end bars 37 connected to each other by a front cross-bar 40 and a rear cross-bar 41, and is supported to travel with the carriage 12. The table 32 is connected with said carriage by rearwardly-extending brackets 42 secured to the under side of the carriage-bar 14 and to the under side of the cross-bar 40 of the relatively fixed section of said table. The table-section 35 is supported at its rear by means comprising brackets 43 secured to the end bars 37 of the relatively fixed table-section 35. The brackets 43 have rollers 44 to run on a rod 45 secured to a frame comprising two end plates 46 extending rearwardly from the main frame 16 of the typewriter. The upper table-section 36 comprises two end bars 47 connected to each other by a front cross-bar 50 and a rear cross-bar 51, the two end bars having rails 52 secured thereto to guide a carbon-carrier 53 towards and away from the platen. The carbon-carrier 53 comprises a base-plate 54, to the under side of which are attached four 95 100 105 110 115 120 125 130

- rollers 55, two at each side of the machine to run on the rails 52. The carbon-carrier further comprises stepped uprights 56, one at each side of the machine, on which carbon-blades or holders 57 are detachably mounted, said carbon-blades having the rear ends of the carbon-sheets 34 connected thereto. The work-web, which may be fan-folded or be composed of separated plies, may be conducted from any suitable source of supply upwardly at the rear of the machine to a turning bar 60, supported by standards 61 and provided with suitable end gages 62 for the web 23. The web is then conducted forwardly through the carbon-carrier and over another turning bar 63 toward the platen. The turning bar 63 is secured to the forward ends of the end bars 47 of the table-section 36, and is provided with suitable end gages 64 to further guide the web. From the turning bar 63 the web is conducted downwardly to the platen, between the feed-rollers 24 and 25 and upwardly at the front across the printing point, where the web may be held against the platen by the usual wing-scales (not shown) and one or more fingers 59 extending rearwardly towards the platen from the usual front rail of the carriage.
- As the typing of a form proceeds, the carbon-carrier 53 travels towards the platen on the table 32. When the typing of a form has been completed, it is desirable to sever the typed forms from the work-sheets. Before this is done, however, it is necessary to shift the carbon-sheets relatively to the work-sheets to bring the leading edges of the carbon-sheets beyond the bottoms of the typed forms, in other words, to shift the carbon-sheets to a fresh set or untyped set of forms. To do this, the composite web is withdrawn around the platen to free it from said platen, so that that portion of the composite web including the carbon-sheets 34 may be brought to a straightened-out position, the platen retaining its usual typing position, after which the work-sheets may be shifted relatively to the carbon-sheets. When it is desired to straighten out the composite web, the feed-rollers 24 and 25 are first cast off by depressing the usual feed-roller release handle 28. The carbon-carrier is then pushed rearwardly by means of a handle 65 extending forwardly therefrom until it is arrested against a fixed stop 66 on the end bar 47, the parts being arrested in the position shown in Figure 3, where the composite web is straightened out, and the leading edges of the work-sheets extend slightly beyond the turning bar 63 and beneath the upper edge of a guide 67 used in reinserting the web around the platen, as hereinafter described.
- After the composite web has been straightened out, as shown in Figure 3, it is desir-
- able to bring it to a position where the leading edges of the work-sheets may readily be grasped, so that the work-sheets may be drawn forwardly while the carbon-sheets are held against movement. To this end the upper section 36 of the table 32 may be swung upwardly at its forward end by means of a handle 70 and about a fulcrum-rod 72 secured to brackets 73 fastened to the cross-bar 41 of the lower table-section 35, said rod being embraced by hinge-like brackets 74 secured to the side bars 47 of the upper table-section. Thus the pivoted table-section is swung to the position indicated in Figure 4, where the web is inclined upwardly and forwardly from the back of the machine. The work-sheets may then be drawn forwardly to a gage 75, said gage determining the extent of shifting of the work-sheets relatively to the carbon-sheets. After the work-sheets have been drawn to the gage they may be severed by a knife 76 arranged beneath the composite web and slightly in advance of the leading edges of the carbon-sheets, as indicated in Figure 5, the severing of the forms being accomplished by drawing the plies against said knife, downwardly towards the platen.
- After the typed forms have been severed from the work-sheets, the swingable table-section is lowered to bring the leading edges of the work-sheets behind the guide 67, the upper end of which is curved rearwardly at 77, so that the composite web may readily be reinserted around the platen, by moving the web forwardly against said guide 67, which directs the web downwardly towards the platen and over the usual paper-table 22, the lower end of which is provided with the usual deflector 78 to guide the web around the platen and upwardly across the printing point. It will be understood that this reinsertion of the composite web may readily be accomplished by hand, but, to expedite the reinserting operation, there is provided web-feeding means which is effective not only to reinsert the web, but to locate it in the proper position around the platen with the first line of writing at the printing point.
- The web-feeding mechanism may comprise two feed-rollers 80 and 81. The feed-roller 80 is disposed beneath the web 23 and is provided with a shaft 82 which may be rotatably supported in the end bars 47 of the pivoted table-section, the feed-roller 81 being disposed directly above the lower feed-roller 80. Said feed-rollers are normally separated, as shown in Figure 1, to afford a free passage of the web therebetween. The upper feed-roller 81 is secured to a shaft 83 rotatably supported in arms 84 extending forwardly from and secured to a rock-shaft 85 pivotally supported in brack-

ets or end plates 86 secured to the sides of the end bars 47 of the pivoted table-section 36, said rock-shaft and said arms forming a sort of frame 87 to support the upper feed-
5 roller 81. The upper feed-roller is normally held away from the lower feed-roller by a return spring 90 connected to a downwardly-extending arm 91 of the feed-roller-carrying frame 87, said arm engaging a stop 10 92 extending inwardly from the right-hand one of the end plates 86. The feed-roller-supporting frame 87 is provided at its right-hand end with an upwardly-extending arm 93 having pivotally supported thereon a 15 feed-roller-operating handle 94 by means of a headed stud 95. The handle or lever 94 is provided with a gear-sector 96 meshing with a pinion 97 secured to the feed-roller shaft 83, so that the feed-roller 81 may be 20 rotated by said operating handle 94. The operating handle 94 is provided with a return spring 94^a, said spring being effective to hold said handle against a fixed stop 94^b, Figure 1, extending from the arm 93 and 25 through a slot 98 in the feed-roller-operating lever.

To reinsert the web around the platen, it is merely necessary to pull forwardly on the feed-roller-operating handle 94 until it is 30 arrested by the stop 94^b which engages the other end of the slot 98, Figure 8. During the initial movement of said lever 94 it swings bodily with the feed-roller-carrying frame 87 until the upper feed-roller 81 is 35 arrested against the lower feed-roller 80, the tension of the return spring 94^a for the lever 94 being, for this purpose, greater than the tension of the return spring 90 connected to the feed-roller-carrying frame 87. After 40 the feed-rollers have been brought together, as in Figure 7, the feed-roller-operating lever 94 has a swinging movement about its pivot 95 to rotate the upper feed-roller 81 by means of the gear-sector 96 and pinion 45 97, said feed-roller being rotated in a counterclockwise direction, to thus advance the work-web 23 against the guide 67, which conducts the web downwardly toward the platen, as previously described. The operator 50 moves said handle until it is arrested against the stop 94^b, as shown in Figure 8, said stop determining the extent of movement required to feed the web with the first line of typing to the printing point. It will 55 be understood that the web is of sufficient stiffness to be pushed around the platen, and that the feed-rollers 24 and 25 are in their released positions at this time. After the web has been reinserted around the platen 60 and located with reference to the printing point, the feed-roller-operating lever 94 and the feed-roller-carrying frame 87 are returned to their normal positions by their return springs. The usual feed-rollers 24 and 65 25 are then thrown on, so that the web may be advanced around the platen, which may be done by the finger-wheel 26 or by the regular line-spacing mechanism including the line-space wheel 27.

The gage 75 is mounted on a gage-bar 100 70 and is adjustably secured thereto for the different lengths of forms. Said gage-bar is secured to a rock-shaft 101 pivoted in the end plates 86 which support the feed-roller frame. Said gage-bar normally occupies the 75 position seen in Figure 1, that it may be out of the path of the work-web so as not to interfere therewith as it is fed upwardly in front of the platen, said gage-bar being swingable forwardly and downwardly to the 80 position indicated in Figure 3, preparatory to a gaging operation, the guide 67 being cut out at 99 to provide clearance for the gage-bar when swung down.

The knife 76 also occupies a normally ineffective position, as indicated in Figure 1, where it is out of the path of the web 23. Said knife comprises two arms 102 extending upwardly therefrom by which it is pivoted on studs 103, so that it may be swung 90 upwardly to its effective position, indicated in Figure 3.

The gage 75 and the knife 76 may be rendered effective simultaneously, by means of the table-lifting handle 70. For this purpose, the handle 70 is connected to the left-hand one of the knife-supporting arms 102, so that, when said handle is swung upwardly, the knife is swung upwardly to its effective position thereby. Extending rearwardly from one or both of the knife-supporting arms may be provided gage-operating arms 104 having pin-and-slot connections 105 with arms 106 secured to the gage-carrying rock-shaft 101, to render the gage 100 effective by means of the handle 70 while the knife is also being brought to its effective position. It will be understood that the handle 70 first has a pivotal movement before the table-section 36 is raised, during 105 which time the gage 75 and the knife 76 are rendered effective. The pivotal movement of said handle 70 ceases when one of the gage-operating arms comes into contact with a stop 107 on one of the side plates, after 110 which the handle is moved bodily to swing the table-section 36 upwardly at the front and about its pivot 72. A return spring 108 is provided, co-operating with one of the gage-operating arms, against the tension of 115 which the gage and the knife may be moved to their effective positions, said spring holding the gage and knife in their normal positions through the medium of the arm 104 which it holds against a fixed stop 110.

To prevent accidental shifting of the carbon-sheets during a work-sheet-shifting operation, the carbon-carrier 53 is held in its retracted position. To this end, the base-plate 54 of the carbon-carrier is provided 120

125

130

with an ear 111 having an opening 112 therein, into which a finger 113, secured to the rod 72 of the fixed table-section 35, passes when the pivoted table-section 36 is swung upwardly to a sheet-gaging position, Figure 4. Thus the carbon-carrier is retained in its rearmost position without any attention upon the part of the operator.

To hold the web-plies or work-sheets 10 against accidental shifting, which may happen while severing the typed forms, there is provided a clamp-element 114 comprising a cross-bar 115 carried by two arms 116 secured to a rock-shaft 117 pivotally supported in brackets 118 extending upwardly from the base-plate 54 of the carbon-carrier. Said clamp-element is normally held in its ineffective position against a fixed stop 120 on an extension 121 of one of the brackets 118, 20 by a return spring 122, and is rendered effective by swinging the pivoted table-section upwardly to the sheet-severing position shown in Figure 6, from the sheet-gaging position shown in Figure 4. To so 25 render the clamp-element effective, there is secured to the end bar 37 of the fixed table-section 35 an upwardly-extending arm 123, which engages a pin 124 on an extension 125 of one of the arms 116 of the clamp-element 114 when the pivoted table-section is swung from the position shown in Figure 4 to the position shown in Figure 6, the cross-bar of the clamp-element being thus swung against the rear turning bar 60, to thus clamp the 30 work-sheets against said bar and consequently prevent accidental forward movement thereof during the severing of the typed forms. The cross-bar 115 of the clamp-element when it engages the turning bar 60 35 serves also to limit the upward swinging of the pivoted table-section and arrests it in its extreme operated position.

By an inspection of Figure 2, it will be seen that the arms 116 are bent inwardly to the clamp-bar 115, which is short enough to fit between the end gages or side guides 62 which are adjustably mounted on the turning bar 60 according to the various widths of webs which may be used in the machine. It will also be seen that the arm 123 is bent laterally into the path of the pin 124 with which it engages to render the clamping element 114 effective.

Detent-springs 126 are provided to hold the forward portion of the table-sections 35 and 36 against each other, said detent-springs being secured to the side bars 37 of the relatively fixed table-section 35, the free ends of said springs being suitably shaped to embrace the cross-bar 50 located at the forward end of the pivoted table-section.

The side bars 37 of the fixed table-section 35 are provided at their forward ends with lugs 130 having cutouts 131 at their upper ends into which the bar 50 of the pivoted ta-

ble section 36 seats itself. Said lugs also engage the end bars 47 on the inside, thus avoiding undue vibrations of the forward portion of the pivoted table-section 36, which may be caused during letter-feeding movements of the carriage.

Variations may be resorted to within the scope of the invention, and portions of the improvements may be used without others.

Having thus described my invention, I claim:

1. In a continuous web typewriting machine, the combination of a carriage, a platen around which a continuous composite web, comprising work-sheets with interleaved carbon-sheets, may be fed, a displaceable table at the rear of the platen, a carbon-carrier to which the carbon-sheets are attached, said carbon-carrier being mounted to travel towards and away from said platen on said table, means to move said carbon-carrier rearwardly to withdraw the composite web around and free of the platen with that portion of the web including the carbon-sheets in straightened-out condition, said platen remaining in printing position, means by which the forward end of said table may be displaced upwardly so that the forward ends of the work-sheets may be grasped to be shifted forwardly and relatively to the carbon-sheets, and a knife carried by said table and disposed beneath the composite web, by which the typed portions of the work-sheets may be severed, said knife being moved from a normally ineffective position to work-sheet-severing position by said table-displacing means.

2. In a continuous billing typewriting machine, the combination of a carriage, a platen around which a composite web, comprising plies of work-sheets with interleaved carbon-sheets, may be fed, means at the rear of the platen to withdraw the composite web around the platen to free it from said platen, means to position that portion of the web including the carbon-sheets inclined upwardly and forwardly from the rear of the machine, and a gage in the path of the web when the latter is in its inclined position, to which the leading edges of the work-sheets may be drawn to shift the work-sheets relatively to the carbon-sheets.

3. In a typewriting machine, the combination of a carriage, a platen on said carriage, means comprising a feed-roller to feed a work-sheet around the platen, said means being arranged at the introductory side of the platen and being independent of said platen, a finger-piece to rotate said feed-roller, means to limit the rotative movement of said feed-roller, and a common support for said feed-roller and said finger-piece, said support being movable to move the feed-roller bodily to bring it into contact with the work-sheet, after which the finger-piece may

be moved relatively to said support to rotate said feed-roller.

4. In a typewriting machine, the combination of a carriage, a platen on said carriage, means comprising a feed-roller to feed a work-sheet around the platen, said means being arranged at the introductory side of the platen and being independent of said platen, a finger-piece to rotate said feed-roller, a common support for said feed-roller and said finger-piece, said support being movable to move the feed-roller bodily to bring it into contact with the work-sheet, after which the finger-piece may be moved relatively to said support to rotate said feed-roller, means to limit the bodily movement of said feed-roller, and means to limit the rotative movement of said feed-roller.

5. In a typewriting machine, the combination of a carriage, a platen on said carriage, means comprising a feed-roller to feed a work-sheet around the platen, said means being arranged at the introductory side of the platen and being independent of said platen, a finger-piece to operate said feed-roller, means to limit the rotative movement of said feed-roller, a common support for said feed-roller and said finger-piece, said support being movable to move the feed-roller bodily to bring it into contact with the work-sheet, after which the finger-piece may be moved relatively to the support to rotate said feed-roller, a table for the work-sheet, and brackets on said table on which said common support is mounted.

6. In a typewriting machine, the combination of a carriage, a platen on said carriage, means comprising a feed-roller to feed a work-sheet around the platen, said means being arranged at the introductory side of the platen and being independent of said platen, a finger-piece to operate said feed-roller, means to limit the rotative movement of said feed-roller, a common support for said feed-roller and said finger-piece, said support being movable to move the feed-roller bodily to bring it into contact with the work-sheet, after which the finger-piece may be moved relatively to the support to rotate said feed-roller, a table for the work-sheet, brackets on said table on which said common support is mounted, a return spring connected between said common support and one of said brackets, and a return spring connected between said common support and said finger-piece.

7. In a continuous web typewriting machine, the combination of a platen around which a composite web, comprising plies of work-sheets with interleaved carbon-sheets, may be fed, means to facilitate straightening out that portion of the web including the carbon-sheets, so that there may be a relative shifting between the work-sheets and the carbon-sheets, a knife for severing the

typed portions of the work-sheets while the web is in its straightened-out position, and means independent of the platen to mechanically present the leading edge of the web to the platen to re-establish the typing relation of the web around the platen.

8. In a continuous billing typewriting machine, the combination of a platen around which a composite web, comprising plies of work-sheets with interleaved carbon-sheets, may be fed, means to facilitate straightening out that portion of the web including the carbon-sheets, so that there may be a relative shifting between the work-sheets and the carbon-sheets, a knife for severing the typed portions of the work-sheets while the web is in its straightened-out position, and means including feed-rollers operable independently of the platen to reestablish the typing relation of the web around the platen.

9. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-sheets from the platen and bring that portion of the web including the carbon-sheets to a straightened-out position, so that the work-sheets may be drawn forwardly over the platen to shift them relatively to the carbon-sheets, a gage to determine the extent of shift of said work-sheets, a knife to sever the typed portions of the work-sheets, and means at the rear of said platen and mounted independently thereof to feed and re-insert the web around the platen to a definite printing position.

10. In a continuous billing typewriting machine, the combination of a carriage, a platen around which a composite web, comprising plies of work-sheets with interleaved carbon-sheets, may be fed, means to so position the web that there may be a relative shifting between the carbon-sheets and the work-sheets, and means to re-establish the printing relation of the web around said platen, said last-named means comprising feed-rollers, one of said feed-rollers being mounted on a pivoted frame, a finger-piece connected to rotate said feed-rollers, a spring to return said finger-piece with respect to said feed-rollers, and a return spring for said frame.

11. In a continuous billing typewriting machine, the combination of a carriage, a platen around which a composite web, comprising plies of work-sheets with interleaved carbon-sheets, may be fed, means to so position the web that there may be a relative shifting between the carbon-sheets and the work-sheets, and means to re-establish the printing relation of the web around said

- platens, said means comprising feed-rollers, one of said feed-rollers being mounted on a pivoted frame, a finger-piece connected to rotate said feed-rollers, a spring to return said finger-piece with respect to said feed-rollers, and a return spring for said frame, the tension of the first-mentioned spring being greater than the tension of the second-mentioned spring, so as to cause the finger-piece to first move bodily with the frame to bring the swingable feed-roller into co-operative relation with the other feed-roller, after which the finger-piece may be rotated against its return spring and relatively to 15 said frame to rotate the connected feed-roller.
12. In a continuous billing typewriting machine, the combination of a carriage, a platen around which a composite web, comprising plies of work-sheets with interleaved carbon-sheets, may be fed, means at the rear of the platen to withdraw the composite web around the platen to free it from the platen and bring it to a straightened-out position, so that the work-sheets may be drawn forwardly over the platen to shift them relatively to the carbon-sheets, a gage to determine the amount of shifting of the work-sheets, a knife to sever the typed portions of the work-sheets, means including feed-rollers to re-insert the work-web around the platen, a handle to actuate said feed-rollers, a stop to limit the motion of said handle to definitely locate the web with respect to 35 the printing point, and feed-rollers co-operating with said platen to advance the web after it has been located.
13. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-sheets from the platen and bring that portion of the web including the carbon-sheets to a straightened-out position, so that the work-sheets may be drawn forwardly over the platen to shift them relatively to the carbon-sheets, means comprising feed-rollers to re-insert the web around the platen, a pinion on one of said feed-rollers, a gear sector meshing with said pinion, a handle to operate said sector to actuate said feed-rollers, and a stop to limit the advancing movement of said handle to feed the web around the platen to a definite position with respect to the printing point.
14. In a continuous web typewriting machine, the combination of a carriage, a platen, in fixed printing position, around which a composite web, including plies of work-sheets with interleaved carbon-sheets, may be fed, means at the rear of the platen to withdraw the composite web around the
- platens to free it from the platen and bring it to a straightened-out position, so that the work-sheets may be drawn forwardly over the platen to shift them relatively to the carbon-sheets, a gage to determine the amount of shifting of the work-sheets, a knife to sever the typed portions of the work-sheets, and web-introducing means including a pair of feed-rollers between which the web passes, the feed-rollers being normally spaced apart so as to allow free passage of the web, and an operating handle effective to cause the feed-rollers to grip the web and then to rotate said feed-rollers to reinsert said web around the platen to 80 a definite location with respect to the printing point.
15. In a typewriting machine, the combination of a carriage, a platen on said carriage, a table to support a work-sheet at the rear of the platen, work-presenting means comprising a feed-roller to feed the work-sheet to and partly around said platen, said means being supported on said table, a finger-piece movable by a single stroke 90 to rapidly rotate said feed-roller, means to limit the rotative movement of said finger-piece and hence said feed-roller, a common support for said feed-roller and said finger-piece, said support being movable on said table to move the feed-roller bodily to bring it into contact with said work-sheet, after which the finger-piece may be moved relatively to said support to rotate said feed-roller, a guide to direct the forward end of 100 the work-sheet presented in a horizontal position downward toward the platen, and a guide at the lower end of the first-mentioned guide to direct the work-sheet around the platen.
16. In a typewriting machine, the combination of a cylindrical platen around which a continuous work-sheet may be fed, a gage to position the work-sheet at various intervals, a knife to sever the typed portion 110 of the work-sheet, two arms on said knife by which the knife is pivotally mounted, one of said arms extending away from said knife beyond its pivot to form an actuating arm, a rock-shaft to support said gage, an arm on said rock-shaft, and a pin-and-slot connection between the arm on the rock-shaft and said actuating arm.
17. In a continuous billing typewriting machine, the combination of a carriage, a platen around which a composite web, comprising work-sheets with interleaved carbon-sheets, may be fed, a table at the rear of the platen connected to travel with said carriage, a carbon-carrier to which the carbon-sheets 125 are attached, said carbon-carrier being mounted to travel towards and away from said platen on said table, means to move said carbon-carrier rearwardly to withdraw the composite web around the platen to free it 130

- from said platen and bring that portion of the web including the carbon-sheets to a straightened-out position, a handle by which the forward end of said table may be swung upwardly, so that the forward ends of the work-sheets may be grasped to be drawn forwardly and relatively to the carbon-sheets, a gage to determine the extent of shifting of the work-sheets, a support for said gage, said support being disposed above the composite web, a knife disposed beneath the composite web by which the typed portions of the work-sheets may be severed, said knife being rendered effective by the table-lifting handle, and a connection from said knife to said gage-support to render said gage effective simultaneously with the knife.
18. In a continuous web typewriting machine, the combination of a carriage, a platen around which a composite web, comprising plies of work-sheets with interleaved carbon-sheets, may be fed, a table at the rear of the platen, said table including two sections, namely, a relatively fixed section and a displaceable section, said table being connected to travel with the carriage, a carbon-carrier to which the ends of the carbon-sheets are attached to travel on the displaceable section towards and away from the platen, means for moving said carbon-carrier rearwardly to withdraw the composite web around the platen to free it from said platen and bring that portion of the web including the carbon-sheets to a straightened-out position, a knife carried by the displaceable section and located beneath the composite web, and means for swinging the forward end of the displaceable section of said table upwardly so that the work-sheets may be readily grasped to shift them relatively to the carbon-sheets, the knife being moved from a normally ineffective position to work-sheet-severing position as a result of the upward swing of the displaceable section.
19. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-sheets from the platen and bring that portion of the web including the carbon-sheets to a straightened-out position, so that the work-sheets may be drawn forwardly over the platen to shift them relatively to the carbon-sheets, a knife to sever the typed portions of the work-sheets while the web is in its straightened-out position, a table at the rear of said platen, over which the web may be conducted to said platen, said table being pivoted so that it may be swung to a convenient position for shifting the work-sheets
- and for severing the typed portions thereof, a handle to lift said table, said knife normally occupying an ineffective position, and a connection between said handle and said knife to render said knife effective.
20. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-sheets from the platen and bring that portion of the web including the carbon-sheets to a straightened-out position, so that the work-sheets may be drawn forwardly over the platen to shift them relatively to the carbon-sheets, a knife to sever the typed portions of the work-sheets while the web is in its straightened-out position, a table at the rear of said platen, over which the web may be conducted to said platen, said table being pivoted so that it may be swung to a convenient position for shifting the work-sheets and for severing the typed portions thereof, a handle to lift said table, said gage and said knife normally occupying ineffective positions, and connections between said handle, said gage and said knife to render said gage and said knife effective during a table-lifting operation.
21. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-sheets from the platen and bring that portion of the web including the carbon-sheets to a straightened-out position, so that the work-sheets may be drawn forwardly over the platen to shift them relatively to the carbon-sheets, a knife to sever the typed portions of the work-sheets while the web is in its straightened-out position, a table at the rear of said platen, over which the web may be conducted to said platen, said table being pivoted so that it may be swung to a convenient position for shifting the work-sheets and for severing the typed portions thereof, means comprising feed-rollers to reinsert said web around said platen after the table has been lowered, said feed-rollers being supported on said table, and means to limit the forward feeding of said web to its printing position.
22. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-

- sheets from the platen and bring that portion of the web including the carbon-sheets to a straightened-out position, so that the work-sheets may be drawn forwardly over the platen to shift them relatively to the carbon-sheets, a gage to determine the extent of shift of the work-sheets, a knife to sever the typed portions of the work-sheets while the web is in its straightened-out position, a table at the rear of said platen, over which the web may be conducted to said platen, said table being pivoted so that it may be swung to a convenient position for shifting the work-sheets and for severing the typed portions thereof, means comprising feed-rollers to re-insert said web around said platen after the table has been lowered, said feed-rollers, said knife and said gage being supported on said table, and means to limit the forward feeding of said web to its printing position. 23. In a continuous web typewriting machine, the combination of a carriage, a platen on said carriage around which a composite web, comprising plies of work-sheets with interleaved carbon-sheets, may be fed, a displaceable table associated with said carriage, over which said web is conducted, a carbon-carrier on said table, to which the ends of the carbon-sheets are attached, means to move the carbon-carrier rearwardly on said table to withdraw the web from the platen, the table being displaced to facilitate relative shifting of the carbon-sheets and the work-sheets, a knife carried by said table to sever the typed portions of the work-sheets, the knife being moved from a normally ineffective position to sheet-severing position upon displacing the table, a clamp for preventing movement of the work-sheets on said table during a severing operation, means associated with said clamp and the table whereby the latter locks said carbon-carrier stationary during said shifting operation, and means carried by the table and coacting with said clamp whereby to render the clamp effective or ineffective. 24. In a continuous billing typewriting machine, the combination of a carriage, a platen on said carriage around which a composite web, comprising plies of work-sheets with interleaved carbon-sheets, may be fed, a straight extension pivoted on said carriage, over which said web is conducted, a carbon-carrier on said extension, to which the ends of the carbon-sheets are attached, means to move the carbon-carrier rearwardly on said extension to withdraw the web around the platen and free the carbon-sheets from said platen, said extension being swingable to an inclined position to bring the web to a work-sheet-shifting position, a knife to sever the typed portions of the work-sheets after shifting, and means to be rendered effective by a further swinging movement of said extension to hold the work-sheets to prevent slipping thereof during a severing operation. 25. In a continuous web typewriting machine, the combination of a carriage, a platen on said carriage around which a composite web, comprising plies of work-sheets with interleaved carbon-sheets, may be fed, a table at the rear of said carriage, over which the web is conducted towards the platen, said table comprising a relatively fixed section secured to said carriage and a pivoted section supported by said fixed section, a carbon-carrier, to which the carbon-sheets are attached, on said table, means to move the carbon-carrier rearwardly on said pivoted section to withdraw the web around said platen to free the carbon-sheets from said platen, means to swing said pivoted section to an abnormal position, so that there may be accomplished a shifting of the work-sheets relatively to the carbon-sheets, a knife to sever the typed portions of the work-sheets, a clamp element on said carbon-carrier, and means on said fixed table-section to actuate said clamp element during a further swinging movement of the pivoted table-section, to cause the clamp element to engage the rear end of the fixed table-section to hold the web to prevent slipping of the work-sheets during a severing operation. 26. In a continuous billing typewriting machine, the combination of a carriage, a platen on said carriage around which a composite web, comprising plies of work-sheets with interleaved carbon-sheets, may be fed, a table at the rear of said carriage, over which the web is conducted towards the platen, said table comprising a relatively fixed section secured to said carriage and a pivoted section supported by said fixed section, a carbon-carrier, to which the carbon-sheets are attached, on said table, means to move the carbon-carrier rearwardly on said pivoted section to withdraw the web around said platen to free the carbon-sheets from said platen, means to swing said pivoted section to an abnormal position to straighten out that portion of the web including the carbon-sheets, so that there may be accomplished a shifting of the work-sheets relatively to the carbon-sheets, a knife to sever the typed portions of the work-sheets, a clamp element on said carbon-carrier, a guide-bar at the rear of the fixed table-section, over which the web is conducted from a source of supply towards the platen, and a finger on said fixed table-section to actuate said clamp element during a further swinging movement of the pivoted table-section, to cause the clamp element to engage said guide-bar to hold the web to prevent slipping of the work-sheets during a severing operation.

27. In a continuous web typewriting machine, the combination of a carriage, a platen around which a composite web, comprising plies of work-sheets with interleaved carbon-sheets, may be fed, a carbon-carrier to which the ends of the carbon-sheets are attached, a displaceable table, said carbon-carrier being retractible on said table to withdraw the web around the platen to free the carbon-sheets therefrom, so that the work-sheets may be shifted relatively to the carbon-sheets, and means, effective at a displacing operation of said table, for locking the carbon-carrier in its retracted position to prevent accidental displacement of the carbon-sheets while the work-sheets are being shifted relatively thereto.
28. In a continuous web typewriting machine, the combination of a carriage, a platen around which a composite web, comprising plies of work-sheets with interleaved carbon-sheets, may be fed, a carbon-carrier to which the ends of the carbon-sheets are attached, a table to support said carbon-carrier, said carbon-carrier being retractible on said table to withdraw the web around the platen to free the carbon-sheets therefrom, so that the work-sheets may be shifted relatively to the carbon-sheets, said table being pivotally supported so that it may be swung to a convenient position to facilitate the sheet-shifting, and means controlled by said table for locking the carbon-carrier in its retracted position, whereby to prevent advancement of the carbon-sheets while the work-sheets are being advanced.
29. In a continuous billing typewriting machine, the combination of a carriage, a platen around which a composite web, comprising plies of work-sheets with interleaved carbon-sheets, may be fed, a carbon-carrier to which the ends of the carbon-sheets are attached, a table to support said carbon-carrier, means to move said carbon-carrier on said table to withdraw the web around the platen to free the carbon-sheets from the platen, so that the work-sheets may be shifted relatively to the carbon-sheets, said table being pivotally supported so that it may be swung to a convenient position to facilitate the sheet-shifting, said carbon-carrier having an opening therein, and a fixed finger to enter said opening to hold the carbon-carrier to prevent the advancement of the carbon-sheets while the work-sheets are being shifted.
30. In a continuous billing typewriting machine, the combination of a carriage, a platen around which a composite web, comprising plies of work-sheets with interleaved carbon-sheets, may be fed, a table at the rear of the platen, over which the web may be conducted to said platen, said table comprising a relatively fixed section secured to said carriage to travel therewith and a pivoted section mounted on said fixed section, a carbon-carrier, to which the ends of the carbon-sheets are attached, mounted on said pivoted section, means to actuate said carbon-carrier to withdraw the web around the platen to free the carbon-sheets from the platen, so that the work-sheets may be shifted relatively to the carbon-sheets, said pivoted table-section being swingable to bring the web to a convenient position for shifting the work-sheets, and means to engage the carbon-carrier, when the pivoted table-section is in its operated position, to hold said carbon-carrier and prevent accidental displacement of the carbon-sheets while the work-sheets are being shifted.
31. In a continuous billing typewriting machine, the combination of a platen around which a composite web, comprising plies of work-sheets with interleaved carbon-sheets, may be fed, means to so condition the web that there may be accomplished a relative shifting between the carbon-sheets and the work-sheets, a carbon-carrier to which the ends of the carbon-sheets are attached, a displaceable table on which said carbon-carrier travels, a latch controlled by said table for holding the carbon-carrier in its retracted position to prevent accidental displacement of the carbon-sheets while the work-sheets are being shifted, a knife for severing the typed portions of the web, and a clamp for preventing slippage of the work-sheets during a severing operation, said knife and the clamp being rendered effective or ineffective by moving said table to different selective positions.
32. In a continuous billing typewriting machine, the combination of a carriage, a platen around which a composite web, comprising plies of work-sheets with interleaved carbon-sheets, may be fed, a carbon-carrier to which the ends of the carbon-sheets are attached, means to actuate said carbon-carrier to withdraw the web around the platen to free the carbon-sheets from the platen, so that the work-sheets may be shifted relatively to the carbon-sheets, means to engage the carbon-carrier in its retracted position to prevent accidental displacement of the carbon-sheets while the work-sheets are being shifted, a knife to sever the typed portions of the work-sheets, a clamp element on said carbon-carrier, a table over which the web may be conducted, said table being swingable to bring the web to a sheet-shifting position, and means on said table to actuate said clamp element during a further swinging movement of the table from the sheet-shifting position to cause the clamp element to engage the rear end of the table to hold the web to prevent slipping of the work-sheets during a severing operation.
33. In a continuous billing typewriting machine, the combination of a carriage, a

platen around which a composite web, comprising plies of work-sheets with interleaved carbon-sheets, may be fed, means to withdraw the composite web around the 5 platen to free the carbon-sheets from the platen and bring that portion of the web including the carbon-sheets to a straightened-out position, so that the work-sheets may be drawn forwardly to shift them relatively to the carbon-sheets, a knife to sever the typed portions of the work-sheets while the web is in its straightened-out position, a table over which the web may be conducted to said platen, said table being pivoted 10 so that it may be swung to a convenient position for shifting the work-sheets and for severing the typed portions thereof, said knife being normally ineffective, and a handle by which the table may be swung and 15 by which the knife may be rendered effective.

34. In a continuous billing typewriting machine, the combination of a carriage, a platen around which a composite web, comprising plies of work-sheets with interleaved carbon-sheets, may be fed, means to withdraw the composite web around the platen to free the carbon-sheets from the platen and bring that portion of the web including 20 the carbon-sheets to a straightened-out position, so that the work-sheets may be drawn forwardly to shift them relatively to the carbon-sheets, a knife to sever the typed portions of the work-sheets while the web 25 is in its straightened-out position, a table over which the web may be conducted to said platen, said table being pivoted so that it may be swung to a convenient position for shifting the work-sheets and for severing 30 the typed portions thereof, said knife being normally ineffective, a handle having a pivotal movement on said table to render said knife effective, and a stop to arrest the pivotal movement of said handle, said handle, 35 after it reaches said stop, being effective to move bodily and swing said table.

35. In a continuous billing typewriting machine, the combination of a carriage, a platen around which a composite web, comprising plies of work-sheets with interleaved carbon-sheets, may be fed, means at the rear of the platen to withdraw the composite web around the platen to free the carbon-sheets from the platen and bring that portion 40 of the web including the carbon-sheets to a straightened-out position, so that the work-sheets may be drawn forwardly over the platen to shift them relatively to the carbon-sheets, a gage to determine the extent of shifting of said work-sheets, a knife to sever the typed portions of the work-sheets while the web is in its straightened-out position, a table at the rear of said platen, over which the web may be conducted to 45 said platen, said table being pivoted so that

it may be swung to a convenient position for shifting the work-sheets and for severing the typed portions thereof, and a handle to render said knife and said gage effective and to lift said table. 70

36. In a continuous billing typewriting machine, the combination of a platen around which a composite web, comprising plies of work-sheets with interleaved carbon-sheets, may be fed, means to so condition the web 75 that there may be accomplished a relative shifting between the carbon-sheets and the work-sheets, a knife to sever the typed portions of the web, a table over which the web may be conducted, said table being 80 swingable to a position where the work-sheets may be severed, and means to be rendered effective to hold the work-sheets when the table is swung to said position, said last-named means serving also to limit the 85 movement of said table.

37. In a continuous billing typewriting machine, the combination of a carriage, a platen on said carriage around which a composite web, comprising plies of work-sheets 90 with interleaved carbon-sheets, may be fed, a straight extension pivoted on said carriage, over which said web is conducted, a carbon-carrier on said extension, to which the ends of the carbon-sheets are attached, 95 means to move the carbon-carrier rearwardly on said extension to withdraw the web around the platen and free the carbon-sheets from said platen, said extension being swingable to bring the web to a sheet-severing 100 position, a knife to sever the typed portions of the work-sheets, and holding means to be rendered effective during the swinging movement of said extension to prevent slipping of the work-sheets during a severing 105 operation, said holding means serving also to arrest the extension in its extreme actuated position.

38. In a continuous billing typewriting machine, the combination of a carriage, a platen on said carriage around which a composite web, comprising plies of work-sheets with interleaved carbon-sheets, may be fed, a table at the rear of said carriage, over 110 which the web is conducted towards the platen, said table comprising a relatively fixed section secured to said carriage and a pivoted section supported by said fixed section, a carbon-carrier, to which the carbon-sheets are attached, on said table, means to move the carbon-carrier rearwardly on said pivoted section to withdraw the web around said platen to free the carbon-sheets from 115 said platen, means to swing said pivoted section to an abnormal position, so that there may be accomplished a shifting of the work-sheets relatively to the carbon-sheets, a knife to sever the typed portions of the work-sheets, a clamp-element on said carbon-carrier, and means to actuate said clamp-ele- 120 125 130

ment during a further swinging movement of the pivoted table-section to cause the clamp-element to engage the rear end of the fixed table-section to hold the web to prevent 5 slipping of the work-sheets during a severing operation, said clamp-element serving also to limit the upward movement of the pivoted table-section.

39. In a typewriting machine, a platen, a 10 platen-carriage, a displaceable table over which a multiple-ply web, interleaved with carbons, may be directed to the carriage, a carrier on the table to which the carbons are connected at their rear, and which is movable 15 toward the platen for line-space feed of the web around the platen in the typing operation, means for moving the carbon-carrier rearward on the table for conditioning the web for relative shift of the carbons 20 and work-webs, the table being effective, when in displaced condition, to lock the carbon-carrier in retracted position preliminary 25 to such relative shift of the carbons and work-webs, a knife moved from a normally ineffective position to web-severing position during the table-displacing operation, the knife being effective to shear the typed portions of the work-webs from untyped portions after such relative shift of 30 the carbons and work-webs, a clamp for gripping the work-webs against displacement during such shearing operation, and a single operating handle associated with said table, the handle effecting displacement of 35 the table, and thereby causing the knife to assume its web-shearing position and the clamp to grip the web.

40. In a typewriting machine, a platen, a 40 platen-carriage, a table over which a multiple-ply web, interleaved with carbons, may be directed to the carriage, a carrier on the table to which the carbons are connected at their rear, and which is movable toward the platen for line-space feed of the web around 45 the platen in the typing operation, means for moving the carbon-carrier rearward on the table for conditioning the web for relative shift of the carbons and work-webs, means for locking the carbon-carrier in retracted 50 position preliminary to such relative shift of the carbons and work-webs, means for severing the typed portions of the work-webs after such relative shift of the carbons

and work-webs, means for clamping the work-webs against displacement during such 55 severing operation, and means common to the carbon-carrier-locking means and the clamp for operating the same; said last-named means acting to lock the carbon-carrier while the clamp is still released, so that 60 the work-webs may be shifted relatively to the carbons, and thereupon acting to clamp the work-webs for severance thereof.

41. In a typewriting machine, a platen, means for clamping a work-web against 65 movement in the machine, a web-severing device movable from a normal position to an effective position, and means common to the clamp and the web-severing device for operating the one in conjunction with the 70 other.

42. In a typewriting machine, a platen, a gage to which a web may be drawn to determine the length to be severed therefrom, a clamp for holding the web against displacement during the severing operation, and means common to the gage and the clamp for operating the one in conjunction with the other, so that the web may first be drawn to position for severing, and thereafter 80 clamped.

43. In a typewriting machine, a platen, a gage to which a web may be drawn to determine the length to be severed therefrom, a web-severing device, a clamp for holding 85 the web against displacement during the severing operation, and means common to the gage, the clamp, and the web-severing device, for operating the one in conjunction with the others. 90

44. In a machine for typing upon a carbon-interleaved work-pack, a platen upon the printing surface of which the carbon-interleaved work-pack is disposable, a carbon-holder, a work-pack clamp on said carbon-holder, a work-web support, a frame movable relatively to said support and upon which said carbon-holder is supportable and means on said support cooperable with said carbon-holder and work-pack clamp to 95 lock the carbon-holder against movement relatively to said frame during one component of the frame's movement and to render said work-pack clamp operative during another component of said movement.

JOHN WALDHEIM.
